UNITED STATES PATENT OFFICE

2,576,930

DEVICE FOR SETTING BACKFIRES

Ambrose B. Everts, Seattle, Wash.

Application April 22, 1947, Serial No. 743,212

2 Claims. (Cl. 126—271.2)

(Granted under the act of March 3, 1883, as amended April 30, 1928; 370 O. G. 757)

1

This application is made under the act of March 3, 1883, as amended by the act of April 30, 1928, and the invention herein described, if patented, may be manufactured and used by or for the Government of the United States of America for governmental purposes without the payment to me of any royalty thereon.

This invention relates to fire control, and has among its objects a device of simple construction for use in setting and controlling back fires.

In the control of fires, it is often desirable to set a back fire a distance at the sides and forward end of the main flame. The back fire is allowed to burn toward the main flame, but is extinguished on the sides remote therefrom, thus providing a burned-out strip which acts as a firebreak to prevent the spread of the main flame beyond the burned-out strip.

The setting of the back fire requires the igniting of the prairie grass, grain field, brush or the like along a line and extinguishing of the line of fire along the side of the line remote from the main flame.

The present invention relates in particular to a device for setting the line of fire and simultaneously extinguishing it along the side remote from the main flame in a rapid manner and with a minimum of man power.

In general, according to the invention, the device is provided with a vertically positioned baffle made of metal or similar non-combustible material on one side of which is positioned a flame thrower to throw a flame downwardly onto the ground and sideways from the baffle, and on the other side of which is positioned a water sprayer for forming a fine spray of water (generally termed a water fog) to throw the water downwardly onto the ground and sideways from the baffle, thus to saturate the combustible material on the ground on that side of the baffle. A land vehicle is provided for conveying the baffle, flame thrower and water sprayer through a field of combustible material with the flame thrower and water sprayer in operation. The result is that the fire is set as the device is moved along, and at the same time the combustible material on that side of the baffle carrying the water sprayer is water soaked, so that the fire is extinguished on that side but allowed to progress on the other side.

For convenience, the baffle is carried on a trailer which may be hitched to a truck with the truck carrying a water supply for the water sprayer and fuel supply for the flame thrower.

The flame thrower and water sprayer are so

mounted as to be readily interchangeable in position relative to the land vehicle. This may be accomplished by reversibly mounting the baffle and attaching the flame thrower and water sprayer to opposite sides of it. It is thus possible by merely properly positioning the baffle to adjust the device so that it may be used on either side of the main flame, or the trailer moved forward in either direction relative to the flame.

For a detailed description of the invention, reference is made to the accompanying drawing, in which

Figure 1 is a left-hand side elevation of the trailer attached to a truck partially shown schematically;

Figure 2 is a top plan view of the baffle carrying the flame thrower and water sprayer and other accessories enlarged over the showing of Figure 1;

Figure 3 is a top plan view of the trailer with the baffle and its attached parts removed;

Figure 4 is a left side elevation of the trailer corresponding to Figure 3;

Figure 5 is an end elevation of the baffle and attached parts;

Figure 6 is a left side elevation of a modified form of the device;

Figure 7 is a plan view thereof;

Figure 8 is an elevation of the baffle corresponding to the showing in Figure 6 but enlarged thereover; and

Figure 9 is an enlarged view corresponding to Figure 6 but with the baffle and parts carried by it reversed.

Referring to the first form of the device, the trailer is provided with a frame 11 in the form of a V-shaped member 12 with couplings 13 and 14 at its forward end for hitching the trailer to a truck. Member 12 has cross braces 15 and 16.

40 A downwardly extending U-shaped member 17 is fastened with its forward leg 18 to brace 16 and its rearward leg 19 to the rearward end of the member 12. Legs 18 and 19 are provided with trough-shaped guides 20 and 21 facing each other, for a purpose later to be described. The frame 11 is supported at its rear by a castor wheel 22 mounted in a bracket 23, the bracket resting on a spring 24 to absorb shock.

U-shaped member 17 rides a few inches above the ground. In order to prevent member 17 from collecting trash or blocking into rocks or the like when the trailer is pulled over rough terrain, a curved deflector 25 is fastened at its forward end to the brace 15 and is integral at its rearward end with the bottom of member 17. This deflec-

tor engages high obstacles and causes the trailer to ride over them.

Baffle 30, in the form of a metallic plate, is generally of rectangular configuration and is positioned in the U-shaped member 17 by sliding its vertical edges downwardly into the U-shaped guides 20 and 21.

One side of the baffle carries a flame thrower, herein shown as of three individual burner units 31, 32 and 33, fixedly mounted on the baffle, a bracket 34 being used for secure attachment of the burner units. As shown, one of the units 32 is positioned to direct the flame downward, while units 31 and 33 are positioned to direct the flame to one side. These individual units are of conventional design and preferably are designed to utilize so-called "bottled gas," a form of fuel gas kept liquid by pressure in the storage tank.

The other side of the baffle carries the water sprayer herein shown as two individual spray nozzles 35 and 36, fixedly mounted on the baffle. These nozzles are of conventional design, nozzle 35 being adjustable by a universal type coupler, so that it may be set at any desired angle. Nozzle 36 is shown as fixed.

A deflector plate 40 is positioned above the nozzles so that the spray hits it and is turned back onto the ground. Plate 40 is demountably attached to baffle 30 by a conventional type hinged joint having a removable hinge pin 41, bracket 42 being provided for supporting the plate 40 in the desired position. Deflector plate 40 may be detached when it is desired to remove the baffle 30 from the carriage to reverse its position.

The flame thrower is supplied with fuel through an upwardly extending rigid pipe 45. A second upwardly extending rigid pipe 46 supplies fuel to a pilot light 47. Upwardly extending rigid pipes 48 and 49 are provided independently to supply water to the spray nozzles.

The trailer is hitched to a truck 55 in any convenient manner. This truck may be a water tank type truck and provided with means for carrying bottled gas. For simplicity in illustration, the truck and parts associated therewith are shown schematically, 56 illustrating the water tank and 57 the bottled gas.

Water is forced from the tank 56 by means of a pump 58 through flexible hose 59 to a panel board 60. This panel board is carried in any convenient place in the truck near the operator. The whole device may be operated by one man, in which event the panel board 60 is positioned in the cab near him. The showing of the panel board is schematic.

Hose 59 is branched at the panel board, one branch 61 leading through valve 62 and the other branch 63 through valve 64. Branches 61 and 63 are also flexible and lead to pipes 49 and 48, respectively. Thus, the operator may, by controlling the valves 62 and 64, supply the nozzles 35 and 36 with water independently at any desired pressure.

Flexible hose 67 leads from gas tank 57 to the panel board, thence through a valve 68 and a flexible hose 69 to the pipe 45 for supplying the flame thrower with fuel. Thus, the operator may by control of valve 68 control the amount of fuel supplied to the flame thrower. Flexible hose 70 runs direct from gas tank 57 through a valve 71 to pipe 46 to supply the pilot light. Valve 71 need not be on the panel board, since ordinarily when the device is used, the pilot light is ignited and burns continuously.

In use, the trailer is coupled to the truck, the

pilot light ignited, with the baffle 30 positioned in the U-shaped guides 20 and 21, with the flame thrower and water sprayer positioned as desired, depending on which side of the main frame the device is to be used for setting the back fire. The operator drives the truck forward along the line to be back fired with the pump 58 in operation and the burners casting the flame. Valves 62 and 64 being opened the desired amount, water from the spray nozzles is ejected as a fog. The part contacting the baffle 30 drips from the lower edge thereof. The result is that the combustible material is thoroughly water soaked on the water sprayer side of the baffle 30, so that the back fire is extinguished on that side but is allowed to progress on the other side.

In general, the form of device shown in Figures 6, 7, 8 and 9 is similar to that before described, but varies somewhat in the structure of the trailer. In this form, the trailer frame 80 is provided with braced arms 81 and 82 having couplings 83 and 84 at their forward ends. A semi-circular shaped beam 85, which may be in the form of a bent pipe, is positioned upright and attached at its forward end to the frame 80, and is provided with side plates 86 and 87 fixedly attached thereto to form the baffle. In this form the castor wheel 88 is positioned at the forward end of the plates 86 and 87. The semi-circular shape of beam 85 provides a deflecting function similar to that described in reference to member 25 of the other form.

In this modification, the burner units and spray nozzles are similar to those used in the other modification, but they are mounted on a generally U-shaped member 90 designed to fit over plates 86 and 87 and be slid downwardly into position with the flame thrower and water sprayer on either side, and held at its edges by guides 91, 92, 93 and 94 attached to the plates, thus to make readily interchangeable the position of the flame thrower and the water sprayer. In this instance, the deflector plate 95 need not be detachably connected to the member 90, since there is no obstruction to removing member 90 with all of its attached parts and reversing it.

Having thus described the invention, what is claimed is:

1. A device for setting and controlling back fires comprising a vertically positioned baffle, a flame thrower positioned on one side of the baffle to throw a flame downwardly and sideways from the baffle onto the ground, a water sprayer positioned on the other side of the baffle for forming a spray of water and throwing it downwardly and sideways from the baffle onto the ground, and a land vehicle for conveying the baffle, flame thrower and water sprayer through a field of combustible material with the flame thrower and water sprayer in operation, whereby a fire is set to the combustible material on the ground on one side of the baffle as the device is moved along and at the same time the combustible material on the other side of the baffle is water soaked so that the fire is extinguished on the water-soaked side but allowed to progress on the other side, the baffle, flame thrower and water sprayer being so mounted on the land vehicle that the flame thrower and water sprayer may be readily interchanged in position relative to the land vehicle, whereby with the land vehicle moving forward the fire may be set on either side thereof depending on the position of the flame thrower and water sprayer, said device being characterized in that the flame thrower and water sprayer are

fixedly mounted on the baffle, the baffle has vertical edges, and the land vehicle has trough-shaped guides into which the vertical edges are slidably mounted, whereby the baffle may be reversed in position thus to make readily interchangeable the position of the flame thrower and water sprayer.

2. A device for setting and controlling back fires comprising a vertically positioned baffle, a flame thrower positioned on one side of the baffle to throw a flame downwardly and sideways from the baffle onto the ground, a water sprayer positioned on the other side of the baffle onto the ground, a water sprayer positioned on the other side of the baffle for forming a spray of water and throwing it downwardly and sideways from the baffle onto the ground, and a land vehicle for conveying the baffle, flame thrower and water sprayer through a field of combustible material with the flame thrower and water sprayer in operation, whereby a fire is set to the combustible material on the ground on one side of the baffle as the device is moved along and at the same time the combustible material on the other side of the baffle is water soaked so that the fire is extinguished on the water-soaked side but allowed to progress on the other side, the baffle, flame thrower and water sprayer being so mounted on the land vehicle that the flame thrower and

water sprayer may be readily interchanged in position relative to the land vehicle, whereby with the land vehicle moving forward the fire may be set on either side thereof depending on the position of the flame thrower and water sprayer, said device being characterized in that the baffle is fixedly attached to the land vehicle and the flame thrower and water sprayer are mounted on a generally U-shaped member which is slidable downwardly into position over the baffle with the flame thrower and water sprayer on either side, thus to make readily interchangeable the position of the flame thrower and water sprayer.
